DESIGN FOR A MEMORANDUM PAD DESK UNIT

Clarence H. Manzler, Rochester, N. Y.

Application March 30, 1940, Serial No. 91,370

Term of patent 7 years

To all whom it may concern:

Be it known that I, Clarence H. Manzler, a citizen of the United States, residing at Rochester, in the county of Monroe and State of New York, have invented a new, original, and ornamental Design for a Memorandum Pad Desk Unit, of which the following is a specification, reference being had to the accompanying drawing, forming a part thereof.

orandum pad desk unit showing my new design and looking at it from the front.

Figure 2 is a perspective view of the memorandum pad desk unit looking at it from the rear.

The dominant features of my design reside in the portions shown in full lines.

I claim:

The ornamental design for a memorandum pad desk unit, as shown and described.

CLARENCE H. MANZLER.
